United States Patent Office

Des. 234,178
Patented Jan. 28, 1975

234,178

ARMOIRE OR SIMILAR ARTICLE

Huey T. Keller, 1609 Davidson Road,
High Point, N.C. 27260

Continuation-in-part of design application Ser. No.
125,452, Mar. 17, 1971. This application Dec. 15,
1972, Ser. No. 315,526

Term of patent 14 years

Int. Cl. D6—04

U.S. Cl. D6—164

Fig.1

Fig.2

FIG. 1 is a view in front elevation of an armoire or similar article showing my design;

FIG. 2 is a view in side elevation; and

FIG. 3 is a plan view thereof.

The side of the armoire not shown is a mirror image of the side shown.

This is a continuation-in-part of design application Ser. No. D. 125,452, filed Mar. 17, 1971 by Huey T. Keller, entitled Furniture Front or the Like.

I claim:

The ornamental design for an armoire or similar article, as shown and described.
